UNITED STATES PATENT OFFICE.

RICHARD M. HOE, OF NEW YORK, N. Y.

METHOD OF SECURING TYPE ON ROTARY BEDS.

Specification forming part of Letters Patent No. 15,501, dated August 5, 1856; Reissued March 22, 1870, No. 3,893.

To all whom it may concern:

Be it known that I, RICHARD M. HOE, of the city, county, and State of New York, have invented a new and Improved mode 5 of Securing Type on Rotary Beds; and I do hereby declare that the following is a full, clear, and exact description of the same, reference being had to the annexed drawings, making a part of this specification, in 10 which—

Figs. 1, 2, 3, 4 and 5, represent each a face view and end view of a segment of a revolving type bed with my improvement applied to it.

15 Similar letters of reference indicate corresponding parts in the several figures.

My invention consists in having the column rules provided with feet which are fitted in rabbets made transversely in the bed, 20 the rabbets having keys inserted in them which fit over ledges or lips on the feet and secure the rules in the bed.

To enable others skilled in the art to fully understand and construct my invention, I 25 will proceed to describe it.

In the annexed drawings, A represents a type bed with its rabbeted grooves for receiving the feet *a*, of the column rules *a'*, and for securing them in their proper places 30 by means of the intermediate pieces *b*, which serve as keys and fit over the lips or ledges *b'*, of the feet *a*, as shown clearly in the transverse section, Fig. 1. The exterior surfaces of the keys *b*, are flush with the surface 35 of the bed A.

B, C, are two flat pieces of metal having one straight edge, while the opposite edges are cut so as to form a series of oblique or wedge-shaped projections *c'* parallel one 40 with the other, and operating precisely in the same manner as a simple wedge and gib. The only object in cutting the edges of the metal strips B, C, into several projections as shown, being simply to reduce the motion 45 or travel of the piece C, which is the wedge, to produce sufficient expansion for compressing the type. The gib piece B, is secured to the surface of the bed by means of feet projecting into the rabbeted grooves and being 50 overlapped by the intermediate pieces or keys *b*, in the same manner as the column rules. The wedge piece C, is prevented from falling out by the insertion of pins *c* projecting from the side in contact with the 55 plate *c'*, and entering grooves *d'*, in said side

plate, which grooves allow the pins sufficient travel, but confine the wedge to the bed.

D, E, are metal strips similar to B, C, respectively, except that instead of being flat they are curved to conform to the surface of the bed. The wedge E being held in its position in the same manner as the wedge C, but the gib D, is secured by mortises made in it opposite the ends of the column rules for the reception of tenons 60 on the ends of said column rules, made for that purpose.

The foregoing description applies to all the figures, the only difference in them being in the manner of driving or drawing 70 the wedges.

In Fig. 1, the wedges are drawn by means of screws underneath the surface of the bed, the nuts having projecting nibs traversing slots in the surface of the bed 75 and extending into mortises in the ends of the wedge pieces E and C.

In Fig. 2, the wedges are pushed forward by screws *f*, *f*, being tapped into the end or side plate and their points being in contact 80 with the rear ends of the wedges E and C.

In Fig. 3, the wedges are drawn by the screws *g*, *g* being tapped in the point edges of the wedges after passing through holes in the side or end plate, the screws having 85 shoulders on the outside to form the resistance.

In Fig. 4, the wedges are urged forward by means of toothed pinions *e*, gearing into racks *e'*, cut in the underside of the wedges having loose cranks or wrenches applied to the shafts of the pinions, also ratchets and pawls attached to the pinions to prevent the possibility of their moving back. In Fig. 5 the usual quoins *a'*, are employed and driven by a shooting stick. I believe this arrangement to be superior to all others known and in present use for the following reasons, viz: Its durability, as it will last in good order as long as the bed itself. Its compactness, a feature often of the first importance. Its economy of the time required to lock up the form. Its perfect safety from the danger of breaking the end or side plates of the bed, which is frequently the case where screws are used, in consequence of the unequal strain imposed on certain points by these methods, but which is obviated in this arrangement by the equal distribution of the whole pressure over the 100 105 110

whole surface of said plates, considerations of the most vital importance to the interests of the daily journal press.

I do not confine myself to any particular means for drawing or driving the wedge plate or strips E, C, for various means and devices may be used for that purpose.

Having thus described my invention, what I claim as new and desire to secure by Letters Patent, is—

Securing or holding the column rules a' , in their places on the bed by means of the

feet a , which fit in rabbeted grooves in the bed and have plates or keys b , fitted over their lips or ledges b' , substantially as shown and described; and I claim this whether the strips or plates B, C, D, E, are used or the usual quoins a^x , or any other device for wedging or binding the type and rules in the bed.

RICH. M. HOE.
